UNITED STATES PATENT OFFICE.

DARWIN D. PARKS, OF STAPLES, MINNESOTA.

CORDING ATTACHMENT FOR SEWING MACHINES.

Application filed April 27, 1925. Serial No. 26,050.

This invention relates to a sewing machine and particularly to a device or attachment for facilitating a cording or piping operation on the sewing machine. Such a 5 cording operation consists in sewing cord between the folded layers of a piece of cloth. Such operations are now quite common with various kinds of cords in making ladies' clothing.

10 It is an object of this invention to provide a simple and efficient means by which the cording operation can be quickly, easily and conveniently performed.

15 It is a further object of the invention to provide such a device in the form of a presser foot having a channel extending longitudinally of its undersurface through which the cord, embraced by the layer of the goods, moves, said channel extending 20 in the line of the feed of the work.

25 It is also an object of the invention to provide such a device in the form of a presser foot having means by which it can be attached to the sewing machine and having 30 a flat undersurface adapted to engage the work, which surface has extending therethrough in the line of the work feed a substantially semi-circular groove, said plate having an aperture therethrough for the passage of the needle.

35 These and other objects and advantages of the invention will be fully set forth in the following description made in connection with the accompanying drawings in which like reference characters refer to the same parts throughout the different views, and in which,

40 Fig. 1 is a view in side elevation of a portion of the sewing machine, the sewing machine table being shown in vertical section;

45 Fig. 2 is a top plan view of the device of the present invention;

50 Fig. 3 is a view in vertical section on the line 3—3 of Fig. 2, as indicated by the arrows; and

55 Fig. 4 is a view in front elevation of the sewing machine parts shown in Fig. 1, the presser foot being shown in engagement with the work.

Referring to the drawings, a portion of a sewing machine is shown, of which it is only necessary to consider the reciprocating needle holder 6^a, the needle 6 held therein by the clamping means 7, the holder 6^a moving through the sewing machine head

8, the bottom portion of which is also shown, and the usual work table upon which the work is supported is shown as 5. The reciprocating presser foot rod or holder 9 60 having thereon a presser foot clamping sleeve 10 is shown held in position by the clamping screw 11. The head portion 10^a is carried by the holder 10 and a clamping sleeve 12 is threaded on the holder 10 so as 65 to clamp down on the slotted portion 14^a of the presser foot member 14. The portion 14^a has a slot 14^b therein. The size of the slot 14^b embraces the stem above the head 10^a and the sleeve 12 is then turned to clamp 70 the portion 14^a against head 10^a. The plate 14 has an intermediate portion 14^c extending at substantially right angles to the portion 14^a and to the lower portion 14^d of the presser foot. The portion 14^d is shaped, 75 as shown in Fig. 2, and has a flat undersurface, said surface having extending therethrough a substantially semi-cylindrical groove 14^e formed by the plate being upwardly bent in a substantially semi-cylindrical form. The groove 14^e is disposed 80 in the line of the work feed and in the embodiment of the invention illustrated, said groove is aligned with the slot 14^b. The portion 14^d of the member 14 has an aperture 85 14^f extending therethrough which extends into the groove 14^e. While this aperture may take various forms, in the embodiment of the invention illustrated, it is shown as substantially square or rectangular in shape 90 and one edge thereof is disposed substantially at the center of groove 14^e.

In operation, the cord used to form the corded material which is illustrated as 15, 95 is embraced by the material 16, as shown in Fig. 4, one edge of the material being folded about the cord 15. It is desired to sew the cord 15 into the goods by a seam extending through the folds of the goods closely adjacent the side of said cord. The goods embracing the cord is placed, as shown in Fig. 4, and the cord and the top layer of the goods are disposed in the groove 14^e, the side of said presser foot portion 14^d above the work coming down in close engagement with the work and placing the goods under some tension about the cord. As the goods is thus held, the needle 6 in its reciprocation, passes through the opening 14^f closely adjacent the side of the cord 15 105 and a seam is thus made along one side of the cord and the cord is neatly and tightly 110

sewed into the goods. The presser foot is, of course, reciprocated in synchronism with the needle, as is the customary operation of the sewing machine.

- 5 From the above description it is seen that applicant has provided a very simple and efficient cording attachment for a sewing machine and one which greatly facilitates the cording operation. The device can be
10 attached to all sewing machines and can quickly and easily be substituted for the usual presser foot thereon. The device is extremely simple and inexpensive in construction. The same has been amply demonstrated in actual practice and found to be
15 very successful and efficient. It will, of course, be understood that various changes may be made in the form, details, arrangement and proportions of the parts without
20 departing from the scope of the applicant's invention, which, generally stated, consists in a device capable of carrying out the objects above set forth, in the novel parts and

combinations of parts disclosed and defined in the appended claims.

25

What is claimed is:

A cording or piping attachment for a sewing machine comprising a member consisting of an integral piece of thin sheet metal having one end disposed substantially in one plane and having converging sides and a central open ended slot adapted to embrace a presser foot carrier and be held thereon and having its opposite end in a lower plane with converging sides, said latter end having a plane undersurface with a substantially central longitudinally extending channel pressed therein, said device having an aperture through said latter end intersecting said channel and slightly to one side thereof, said plate having a substantially vertical plane portion between said ends.
